(57) **CLAIM**

The ornamental design for a dual pulley for exercise equipment substantially as shown and described.

DESCRIPTION

FIG. 1 is a top, front, right isometric view of a dual pulley for exercise equipment depicted in an environment of a portion of a weight-lifting rack.

FIG. 2 is a top, front, right isometric view of the dual pulley for exercise equipment of FIG. 1.

FIG. 3 is a bottom, rear, left isometric view of the dual pulley for exercise equipment of FIG. 1.

FIG. 4 is a front elevation view of the dual pulley for exercise equipment of FIG. 1.

FIG. 5 is a rear elevation view of the dual pulley for exercise equipment of FIG. 1.

FIG. 6 is a right side elevation view of the dual pulley for exercise equipment of FIG. 1.

FIG. 7 is a left side elevation view of the dual pulley for exercise equipment of FIG. 1.

FIG. 8 is a top plan view of the dual pulley for exercise equipment of FIG. 1; and,

FIG. 9 is a bottom plan view of the dual pulley for exercise equipment of FIG. 1.

The dot-dash-dot lines shown in FIG. 1 of the drawings are for purposes of illustrating use and environment only and form no part of the claimed design. The uniform dashed lines illustrate unclaimed features of the dual pulley for exercise equipment design and form no part of the claimed design.

1 Claim, 9 Drawing Sheets
